Primary Examiner — Paula Allen Greene

(57) **CLAIM**

The ornamental design for a headphone and stand, as shown and described.

DESCRIPTION

FIG. 1 is a top perspective view of a headphone, of the headphone and stand, showing my new design; the headphone is shown separately for ease of illustration;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a stand for a headphone and stand thereof, the stand is shown separately for ease of illustration;

FIG. 10 is a bottom perspective view of another embodiment thereof;

FIG. 11 is a front view of another embodiment thereof;

FIG. 12 is a rear view of another embodiment thereof;

FIG. 13 is a left side view of another embodiment thereof;

FIG. 14 is a right side view of another embodiment thereof;

FIG. 15 is a top view of another embodiment thereof;

FIG. 16 is a bottom view of another embodiment thereof;

FIG. 17 is a perspective view of the headphone and stand thereof;

FIG. 18 is an enlarged detail view of area 18 in FIG. 1 thereof; and,

FIG. 19 is an enlarged detail view of area 19 in FIG. 1 thereof.

The broken lines in the drawings illustrate the portions of the headphone and stand, which form no part of the claimed design.

The dash-dot-dash broken lines encircling the enlarged views are for annotative purposes only and form no part of the claim thereof.

1 Claim, 19 Drawing Sheets
